[57] CLAIM

The ornamental design for a cream pitcher or the like, as shown and described.

DESCRIPTION

FIG. 1 is a side elevational view of a cream pitcher or the like showing my new design, with the side opposite that shown being a mirror image thereof.

FIG. 2 is a front elevational view.

FIG. 3 is a rear elevational view.

FIG. 4 is a top plan view.

FIG. 5 is a bottom plan view.
